SHADE ROLLER

Fred J. Burns, Saginaw, Mich., assignor to The Columbia Mills, Inc., Saginaw, Mich., a corporation of New York

Application January 12, 1935, Serial No. 1,511

5 Claims. (Cl. 156—35)

This invention relates to shade rollers, and more specifically to a detachable means whereby the conventional roller may be readily adapted for what is generally termed "bottom-up" shade operation, where the roller is mounted below and the shade is pulled upwardly.

The prime object of the invention is to provide a very simple and inexpensive clip or attachment for holding the upper conventional roller pawl out of engagement with the ratchet.

Another object is to provide an attachment which can be readily and easily placed in position, and to so form the roller hub as to accommodate said attachment.

The above and other objects will appear as the specification progresses, reference being had to the accompanying drawing in which I have shown the preferred embodiment of my invention, and in which like reference numerals indicate like parts throughout the several views thereof.

In the drawing—

Fig. 1 is an enlarged fragmentary sectional view of a shade roller showing my attachment in place.

Fig. 2 is an enlarged end view.

Fig. 3 is a front view of the notched hub.

Fig. 4 is a sectional edge view.

Fig. 5 is an enlarged perspective view of the attachment.

Fig. 6 is an elevational view showing a shade roller mounted for bottom-up operation.

Referring now more particularly to the drawing in which I have shown the preferred embodiment of my invention, the numeral 5 indicates a standard wood roller, this is suitably bored as shown at 6 to accommodate the winding mechanism, which includes a spindle 7 having a winding spring 8 anchored to the inner end thereof, a spindle ferrule 9 fits over the opposite end of the spindle, and a conventional spear 10 is mounted in this outer end, and is shouldered as shown at 11 to accommodate a ratchet and hub 12 and 13 respectively.

A spool bearing 14 is mounted on the spindle ferrule as shown, and a spool 15 is mounted thereon and is provided with laterally projecting ears (not shown), which pierce the end of the roller and which also serve as an anchorage for the end of the winding spring, spaced apart rivets 16 being mounted on the spool, and pawls 17 are pivotally mounted on said rivets and are adapted to engage the ratchet 12 in the usual manner, this arrangement, however, forms no part of the present invention, the purpose of

the description being to show the relation of the winding mechanism to the attachment, so that its function may be readily understood.

The outer rim of the hub 13 is notched as clearly shown at 18 in Fig. 3 of the drawing, and is adapted to accommodate the leg 19 of the spring clip or attachment 20 which is formed as clearly shown in Fig. 5, said clip being formed with an opening 21 so that it may be mounted on the spear, the leg being slightly bowed or crimped as shown at 22, so that it resiliently engages the rim of the hub, and when the clip is in position as shown in Figs. 1 and 2 of the drawing, this leg 19 projects into and covers one of the notches 23 in the ratchet, preventing engagement of the pawl with the notch, so that said pawl and ratchet notch are rendered inactive.

In so called "bottom-up" shade operation, the roller is mounted at the bottom or in any position intermediate the length of the window to permit of ventilation, etc., and it is often mounted adjacent the top of the lower sash, an additional shade roller being provided for the lower sash and is operable in the conventional manner (the shade being pulled downwardly), these rollers being mounted to overlap to exclude light at that point, consequently, the shade which is mounted for "bottom-up" operation is operated in an entirely different manner, and the roller pawls must be inactive to permit said operation, and I have therefore perfected a very simple, practical and inexpensive attachment, which can be easily and quickly applied, and by use of which standard shade rollers can be used for "bottom-up" shade operation, or in any other position requiring a single notch shade roller, or a roller having no notches, thereby eliminating the necessity of manufacturing and stocking both single and double notch rollers, as well as the special brackets oftentimes used for this purpose, and which permit the permanent disengagement of the pawls once the shade is operated and the pawls become disengaged.

When using a shade roller for this "bottom-up" operation, the spring clip is first inserted, the roller is manipulated to properly tension the winding mechanism, it is then mounted in the brackets 24 with the live pawl and ratchet notch at the bottom of the roller, and when the shade is operated, the pawl disengages from the notch and drops downward into inactive position and so remains.

A ring 25 is usually provided on the end of the shade 26, and an operating cord 27 is anchored thereto, said cord leading up and over

55

the usual locking sheave 28 provided on the head casing of the window frame, the cord thence leading downwardly so that it is within easy reach for operation.

5. It will, of course, be obvious that two legs may be provided on the clip so that both pawls are held out of engagement, but I find that the clip as shown operates entirely satisfactorily.

10. From the foregoing description it will be obvious that I have perfected a very simple, practical, and economical clip attachment for converting standard shade rollers so that they are readily applicable for "bottom-up" shade operation.

What I claim is:

15. 1. A clip attachment for shade rollers, comprising a stamped body member provided with a centrally disposed opening therein, and a laterally extending resilient leg formed integral with said body member, the inner end of said leg being crimped for engaging a roller hub.

20. 2. The combination with a shade roller provided with the usual roller pawls and ratchet, of a roller hub, a clip mounted on said roller, said clip being formed with a laterally projecting leg

resiliently engaged with said hub for holding the roller pawls out of engagement with the roller ratchet.

3. The combination with a shade roller having a notched roller hub and the usual roller pawls and ratchet, of a detachable clip mounted on said roller, said clip being provided with a laterally projecting leg for holding the roller pawls out of engagement with the ratchet.

4. The combination with a shade roller having a notched roller hub and the usual roller pawls and ratchet, of a clip resiliently mounted on said roller, and formed with a laterally projecting resilient leg, said leg projecting through said notch, and being adapted to hold the roller pawls out of engagement with the roller ratchet.

5. The combination with a shade roller having a notched hub, roller pawls and notched ratchet, of a quickly detachable means mounted on said roller and extending through said notch for holding the roller pawls out of engagement with the roller ratchet notch.

FRED J. BURNS.
